UNITED STATES PATENT OFFICE.

LEONARD B. WORDEN, OF PENN YAN, NEW YORK.

LEVELING AND PLUMBING INSTRUMENT.

1,006,818.

Specification of Letters Patent. Patented Oct. 24, 1911.

Application filed April 19, 1911. Serial No. 622,107.

To all whom it may concern.

Be it known that I, LEONARD B. WORDEN, a citizen of the United States, residing at Penn Yan, in the county of Yates and State 5 of New York, have invented a new and useful Leveling and Plumbing Instrument, of which the following is a specification.

My invention relates to improvements in leveling and plumbing instruments.

10 The invention has for its object to provide for readily and conveniently ascertaining the required pitch or angle in any given piece of work where this may be wanted.

Further objects are also to provide a leveling instrument in connection with the pitch determining member, and to carry out these ends in a simple, effective and inexpensive manner.

20 The invention consists of certain instrumentalities and features substantially as hereinafter fully disclosed and defined by the claims.

In the accompanying drawing illustrating the preferred embodiment of my invention 25 wherein it will be understood various changes and modifications may be made as relates to the construction and arrangement of the details of the parts without departing from the spirit of my invention: Figure 1 is a side 30 or face view of the invention as adjusted for the horizontal, the index registering with the initial graduation or mark. Fig. 2 is a similar view of the device with a portion thereof broken away and other parts in section, dis- 35 closing more especially the cam of the index-carrying member or pin and its receiving slot, also the arcuate guide-slot for the guide-pin or stud of the spirit-level carrying member. Fig. 3 is a sectional plan view of the 40 same, the section being produced just below the spirit glass. Fig. 4 is a vertical or transverse section taken about centrally through the device.

In carrying out my invention I suitably 45 secure preferably to a bar plate 1 parallel upstanding plates or supports 2 having lateral bottom-edge extensions 2^a by suitable fastenings, as screws or rivets passing through said extensions, said base plate in 50 turn being secured in practice, to a "straight-edge" member, not shown.

A suitably edgewise-disposed plate or member 3 is arranged to have movement between the plates or supports 2, it being piv- 55 otally supported in relatively elevated posi-

tion, upon a suitable pivot or pin 4, which may, in practice, be simply a stub-screw, passed through registering apertures 4^a in said plates, which apertures may be duplicated as at 4^b for obvious reasons. Said 60 plate or member 3 carries upon its upper edge, at the ends tubular formations, sleeves, or sockets 5 for the reception, or insertion thereinto, of the ends of a spirit-glass 6 of the well-known type, said spirit-glass being 65 frictionally held in place as will be readily appreciated.

An axial stud or member 7 which has its bearings in alining apertures 8 in the up-standing plates or supports 2, a short dis-tance above the lower edges thereof, has 70 fixed about centrally thereof a cam 9 play-ing or received within a slot 10 produced in the pivoted plate or member 3 bearing the spirit glass or leveling member, said cam 75 engaging the edges or walls of said slot. Said axial stud or member carries an index-member or pointer 11 arranged to play over a graduated quadrant 12 formed by suitably scribing the usual degree-indicating lines or 80 marks upon the outer surface of one of the lateral upstanding plates or supports 2, as clearly disclosed by Fig. 1.

In the spirit-glass or level bearing or carrying member 3 is an arcuate slot 13 ex-tending in a general inclined direction, 85 which receives a stud or pin 14 from one of the upstanding plates 2 for limiting or con-trolling the tilting or oscillating movement of the member 3 while being used, which 90 stud or pin may be a stub-screw in practice.

It is apparent that, as the straight-edge member above noted is suitably applied to the object or piece of work, where it is re-95 quired to ascertain a given pitch or angle of inclination, this will be indicated with the movement of the index or pointer 11 car-ried by the axial member 7, playing above the graduations 12 as the axial member is moved or actuated by the engagement of 100 the cam 9 with the walls of the slot 10 of the level or spirit-glass carrying member 3 in conforming to the horizontal, as is ap-105 parent. Any degree of inclination, or pitch, may be indicated by the use of this instru-110 ment, included from the initial point to forty-five degrees.

This instrument, it will be observed, is ex-tremely simple, ready of operation, effective and accurate in action and inexpensive of 110

manufacture, while the spirit-glass may be used as a leveling instrument alone, as is readily apparent.

I claim:

5 1. A device of the character described, including a supporting member, a graduated member attached thereto, a member carrying a spirit-glass, said spirit-glass carrying member and said graduated member having pivotal connection, and an axial member carried by said spirit-glass carrying member and itself provided with an index registering with the graduations of said graduated member, said axial member also carrying a cam engaging said spirit-glass carrying member.

2. A device of the character described, including a supporting member, parallel spaced-apart members attached to said supporting member, one of said parallel members being graduated, a member carrying a spirit-glass and having pivotal connection with, and arranged intermediate said parallel members and an axial member carried by said parallel members and having an index

registering with the graduations of the graduated member, said axial member also being provided with a cam engaging said spirit-glass carrying member.

3. A device of the character described, including a supporting member, parallel spaced-apart members attached to said supporting member, one of said parallel members being graduated, a member carrying a spirit-glass and arranged intermediate, and 35 pivotally connected to said parallel members and having a vertical slot therein, and an axial member carried by said parallel members and having an index registering with the graduations of the graduated member, said axial member also having a cam engaging the walls of said slot.

In testimony that I claim the foregoing as my own, I have hereto affixed my signature in the presence of two witnesses.

LEONARD B. WORDEN.
